US0D1054780S

(12) United States Design Patent (10) Patent No.: US D1,054,780 S
(45) Date of Patent: * Dec. 24, 2024

(54) BOTTLE LID

(71) Applicant: Honglin Wu, Chuzhou (CN)

(72) Inventor: Honglin Wu, Chuzhou (CN)

() Term: 15 Years

(21) Appl. No.: 29/942,542

(22) Filed: May 16, 2024

(51) LOC (14) Cl. 07-02

(52) U.S. Cl.

USPC D7/392

(58) Field of Classification Search

USPC D3/202, 302; D7/300, 387, 392, 392.1, D7/300.2, 301, 313, 391-393, 394, 396.1, D7/396.2, 397, 398, 412, 415, 507, 509, D7/510, 511, 518, 521, 538-542, 629, D7/900; D9/434-436, 438-441, D9/443-447, 449-454, 503-505, 523; D8/349, 354

(57) CLAIM

The ornamental design for a bottle lid as shown and described.

DESCRIPTION

FIG. 1 is a perspective view of a bottle lid, showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the bottle lid that form no part of the claimed design.

1 Claim, 8 Drawing Sheets
